UNITED STATES PATENT OFFICE.

EDWARD H. GRIM, OF DOTT, WEST VIRGINIA.

ELECTRICAL SWITCH-OPERATING MECHANISM.

Application filed March 21, 1925. Serial No. 17,358.

To all whom it may concern:

Be it known that I, EDWARD H. GRIM, citizen of the United States, residing at Dott, in the county of Mercer and State of 5 West Virginia, have invented certain new and useful Improvements in Electrical Switch-Operating Mechanism, of which the following is a specification.

This invention relates to an electrical 10 switch operating mechanism, particularly useful in connection with the switches of haulage railways in coal mines and the like.

An object of the invention is to provide means under control of the motorman of a 15 mine locomotive for selectively shifting the pair of cooperating switch points of each railway switch in the mine to the desired one of its operative positions, while the locomotive is in motion and approaching the switch.

20 Another object is to minimize the occurrence of wrecks by providing means for maintaining the points of a switch in the position to which they have been shifted and preventing them from being shifted to their 25 other positions substantially until the locomotive and any cars coupled thereto have passed the switch.

A further object is to provide railway 30 switch operating and controlling means of the above kind which are simple and durable in construction as well as efficient in operation.

With the above general objects in view, and others that will become apparent as the 35 nature of the invention is better understood, the same consists in the novel form, combination and arrangement of parts hereinafter more fully described, shown in the accompanying drawings, and claimed.

40 In the drawings, wherein like reference characters indicate corresponding parts throughout the several views.

Figure 1 is a fragmentary plan view illustrating a portion of a railway equipped 45 with a switch operating mechanism constructed in accordance with the present invention.

Figure 2 is a fragmentary side elevational view, partly broken away, showing part of 50 the controlling means for the switch actuated mechanism together with the latter and their relation to the rails of the main track of the railway.

Figure 3 is an enlarged transverse section- 55 al view illustrating a mine locomotive, posi-

tioned upon the railway tracks and associated with controlling means for the switch operating mechanism, constructed in accordance with the present invention.

Figure 4 is a side elevational view of the 60 device shown in Figure 3,

Figure 5 is an enlarged fragmentary sectional view showing one of the switch actuating solenoids in central longitudinal section. 65

Figure 6 is a fragmentary enlarged plan view illustrating the switch forming part of the means for maintaining the points of the switch in the position to which they have been shifted. 70

Figure 7 is a side elevational view of the device shown in Figure 6 and

Figure 8 is an enlarged transverse sectional view taken substantially upon a line 8-8 of Figure 1. 75

Referring more in detail to the drawings, 5 generally indicates the main track of the railway and 6 a branch track thereof, the usual switch points 7 being provided for controlling passage of the rolling stock at 80 the point where the switch is provided, whereby the rolling stock may be caused to continue on through the main track or to be switched therefrom onto the branch track 6, as is well known in the art. 85

A switch bar 8 connects the free ends of the switch points 7 in the usual manner, whereby movement of said bar will cause simultaneous shifting of the switch points. 90 In accordance with the present invention, the switch bar 8 has its ends projecting outwardly beyond the rails of the track at opposite sides of the latter and these ends are respectively pivoted as at 9 and 10 to the cores 11 and 12 of solenoids 13 and 14. 95

As shown in Figures 3 and 4, the conventional mine locomotives are of low built construction, and these locomotives usually carry a trolley, by means of which current is collected for the actuation of their driving motors, from a trolley wire (not shown), usually suspended from the roof of the mine. The locomotive is indicated generally by the reference character 15 and the return of the current from the motor of the 100 locomotive is generally secured by grounding the same to the frame of the locomotive so that the return current will pass back to the generator at the power house by way of the rails 16, on which the wheels of the lo- 105

- comotive run. The feed wires 17 of the solenoids 13 and 14 are adapted to be connected with the trolley wire by means of a wire 18.
- 5 An auxiliary trolley wire 19 is mounted along one side of the track some distance to the left of the switch shown in Figure 1, and arranged to be swung upwardly into engagement with this auxiliary trolley wire 19 is a lever 20 pivoted between its ends as at 21 upon the locomotive 15. The auxiliary trolley wire 19 is shown as having its ends clamped between insulating blocks 22 suitably secured to the upper ends of posts 15 or standards 23 mounted upon spaced ties 24 of the railway tracks. However, the auxiliary trolley wire 19 might of course, be readily suspended from insulators or insulator brackets secured to the wall of the 20 mine, and the use of supporting standards 23 is merely given as an example. It is to be understood that the pair of cooperating posts 23 are separated some distance so as to give the auxiliary trolley wire 19 a considerable length. Also, the lever 20 may be provided with any suitable means for facilitating its manual actuation by the motorman of the locomotive 15, and as 25 shown, this consists of a link 25 having one end attached to the inner end of the lever 20 and its other end attached to a weighted lever 26 pivoted upon the locomotive 15 inwardly of the lever 20. The lever 26 will of course be insulated from the lever 20 so that 30 the operator may manipulate the same without danger of shock. The auxiliary trolley wire 19 is connected by means of a wire A to the negative side of the solenoid 14 which solenoid is also connected at this side by 35 means of a wire 27 with the stationary contact 28 of a two-way switch.
- A second auxiliary trolley wire 19^a is supported alongside of the track in tandem relation to the trolley wire 19 by means of 40 further supporting standards 23^a mounted upon others of the ties 24 and the ends of said trolley wire 19^a are secured in insulating blocks 22^a suitably secured in the upper ends of said standards 23^a.
- 45 As will be seen from Figures 1 and 2, the second auxiliary trolley wire 19^a is connected by means of a wire B with the negative side of the coil of the solenoid 13, and this side of the latter coil is also connected 50 by means of a wire 29 with the second stationary contact 30 of said two-way switch mentioned above. This two way switch preferably embodies the contacts 28 and 30 fixed upon an insulating plate 31 securely 55 fastened upon the adjacent tie 24, the contacts 28 and 30 projecting toward the adjacent switch bar 8 and cooperating with a contact 32 secured to said switch bar 8 and insulated from the latter as indicated 60 at 33. As shown in Figures 6 and 7, the
- movable contact 32 carried by the switch bar 8 may be secured to the insulating block 33 and the latter may be suitably rigidly secured to the switch bar 8 so as to move therewith when the switch points 7 are shifted, the contact 32 engaging the contact 30 when the points 7 are positioned as shown in Figure 1, to permit passage of the rolling stock through on the main track, and said contact 32 being arranged to engage the contact 28 when the switch points 7 are shifted so as to cause the rolling stock to pass from the main track onto the branch track 6.
- 65 As shown in Figures 1 and 8, a ramp 34 is disposed beside a rail of the main track 5 in advance of the switch points 7 and this ramp is yieldingly held elevated, so as to be depressed by wheels of the rolling stock travelling on the rails 16, by means of 70 springs 35, which springs encircle depending pins 36 carried by the ramp 34 and movable in guides 37 of brackets 38 fixed to adjacent ties 24. A contact strip 39 is attached to the ramp 34 and insulated therefrom as indicated at 40, and this contact strip 39 is adapted to engage the base of the adjacent rail 16 when the ramp 34 is depressed, and to disengage from the base of the rail when allowed to rise under the influence of the springs 35. The contact strip 39 is connected by means of a wire 41 with the movable contact 32 of the two way switch, as shown clearly in Figure 1. It is 75 to be noted that the ramp 34 is disposed adjacent to the switch points 7.
- If the frame of the locomotive 15 is constructed of wood, the pivot 21 of the lever 20 may be electrically connected with the axle of the locomotive wheels by means of 80 a suitable conductor, and where animal haulage is employed, the lever 20 may be pivoted to the side of a leading coal car.
- 85 In operation, assuming that the parts are positioned as shown in Figure 1, and that the locomotive 15 is approaching the switch points 7 from the left of Figure 1, and also assuming that the motorman desires to continue on through the switch on the main track, the lever 21 is swung upwardly into 90 engagement with the auxiliary trolley wire 19. When this is done the current will flow from the trolley wire by way of a wire 18 and the feed wire 17 of solenoid 13 to wire B and trolley wire 19^a, the current then 95 passing to the rails 16 through the frame of the locomotive by way of lever 20. The circuit of solenoid 13 is thus closed so as to cause energization of the coil of said solenoid 13 whereby its core 11 is attracted 100 for drawing the switch bar 8 toward said solenoid and insuring positioning of the points 7 as shown in Figure 1. Of course, if the motorman had known that the points 105 were properly positioned, the necessity of 110
- 115
- 120
- 125
- 130

this operation would be eliminated, but, as the position of the points is not known in advance, this operation will be effected at all times. When the switch bar 8 is thus shifted, the contact 32 engages the contact 30 so that the current is shunted by way of wire 29 from the coil of solenoid 13 to the wire 41 by way of contacts 30 and 32 and then to the conducting strip 39. As the strip 39 is maintained in engagement with the base of the rail 16 by passage of the wheels of the locomotive and cars coupled thereto over the ramp 34, the circuit of the solenoid 13 is maintained closed for preventing the points 17 from being shifted to their other position until after all of the wheels of the rolling stock have passed over said ramp 34 and substantially passed the switch points 7. If the motorman had desired to pass onto the branch track 6, the lever 20 would have been swung into engagement with the trolley wire 19 so as to cause the core 12 of solenoid 14 to be attracted. This would effect movement of the points 7 and switch bar 8 toward the solenoid 14 so that the contacts 28 and 32 would be engaged and whereby the circuit of solenoid 14 is maintained closed by means of the wheels passing over the ramp 34.

From the foregoing description, it is believed that the construction and operation as well as the advantages of the present invention will be readily understood and appreciated by those skilled in the art.

What I claim as new is:—

1. The combination with the switch points of a railway switch, of a solenoid for shifting said switch points in one direction, a second solenoid for shifting said switch points in an opposite direction, and means including an element on a vehicle of the railway operable to selectively close the circuit of either desired one of said solenoids while the vehicle is in motion and approaching said railway switch, a normally open current grounding switch operatively associated with a rail of the railway adjacent the switch points and movable by the wheels of rolling stock of the railway to closed position, and means operable by shifting of the

switch points to connect the operative solenoid to said current grounding switch and simultaneously disconnect the inoperative solenoid from said current grounding switch.

2. The combination with the switch points of a railway switch, of a solenoid for shifting said switch points in one direction, a second solenoid for shifting said switch points in an opposite direction, and means including an element on a vehicle of the railway operable to selectively close the circuit of either desired one of said solenoids while the vehicle is in motion and approaching said railway switch, a normally open current grounding switch operatively associated with a rail of the railway adjacent the switch points and movable by the wheels of rolling stock of the railway to closed position, and means operable by shifting of the switch point to connect the inoperative solenoid to said current grounding switch and simultaneously disconnect the inoperative solenoid from said current grounding switch, said last named means including a two-way electrical switch having a movable contact element fixed to and movable with the switch bar of the switch points.

3. The combination with the switch points of a railway switch, of a motor for shifting said switch points in one direction, a second motor for shifting said switch points in an opposite direction, and means including an element on a vehicle of the railway operable to selectively render either desired one of said motors operative while the vehicle is in motion and approaching said railway switch, a normally open motor controlling element operatively associated with a rail of the railway adjacent the switch points and movable by the wheels of rolling stock of the railway to closed position, and means operable by shifting of the switch points to connect the operative motor to said control element and simultaneously disconnect the inoperative motor from said control element.

In testimony whereof I affix my signature.

EDWARD H. GRIM.
